UNITED STATES PATENT OFFICE.

ANTHONY G. BRUNSMAN, OF CINCINNATI, OHIO.

VEHICLE-BODY.

SPECIFICATION forming part of Letters Patent No. 761,816, dated June 7, 1904.

Application filed December 10, 1903. Serial No. 184,602. (No model.)

To all whom it may concern:

Be it known that I, ANTHONY G. BRUNSMAN, a citizen of the United States, residing in Cincinnati, county of Hamilton, and State of Ohio, have invented certain new and useful Improvements in Vehicle-Bodies, of which the following is a full, clear, and exact description, reference being had to the accompanying drawings, forming part of this specification.

10 My invention relates to the construction of vehicle-bodies for buggies; and it has for its object to keep the body of the vehicle from becoming loose in the framework, and thus loosening the panels and opening up of the body at the corner.

15 The invention consists of that certain novel construction and arrangement of parts to be hereinafter particularly pointed out and claimed, whereby the seat-buck is braced and strengthened, so as to become rigid and secure against the racking strain to which the seat construction of such vehicle is submitted. Seat-risers are usually provided for such vehicle-bodies, so that the seat itself and the 20 strains to which it is submitted have a tendency to weaken and open up the panels of the seat-body at the corners.

25 In the drawings, Figure 1 is a perspective view of my improvements with the seat itself removed. Fig. 2 is a perspective view of one of the corner-irons.

30 A A are the side panels, and B C the front and rear panels, of an ordinary vehicle-body. These panels are secured to the sill D of the body and are braced together at the corners by the corner-posts a a and b b.

35 E E are the seat-risers for sustaining the seat, mounted on the side panels at the proper position. These seat-risers and the seat itself are braced and supported by the usual seat-buck, which consists of the upright corner-posts e e, mounted and secured on the sill D and provided with the end pieces e e and the cross-bars f f to make a substantial framework. As has been intimated, this framework, 40 however, is not sufficiently strong and rigid to bear the strains to which it is subjected without the support of the side panels and seat-risers, so that in the ordinary construction, the strain is transmitted to the side panels

and there is a tendency for them to weaken or open up at the corners. To overcome this difficulty, I provide as follows: F represents corner-irons or metallic plates provided with a flat upper surface g to embrace the top surface of the seat-buck frame at the four upper corners and with a flange h to engage the side pieces f f of the seat-buck and a tongue or lip l to be sunk into the upper surface of the seat-risers. Passing through the openings m in the flanges h of the corner-irons are the horizontal bolts n, which run from the front to the rear and can be properly tightened by the nuts on the ends of the bolts. p p are the seat-bolts, which are of sufficient 55 length to extend from the seat down through the openings r in the corner-irons and through the sill D. Instead of using the seat-bolts p p for securing the seat and at the same time strengthening the seat-buck vertically separate seat-bolts may be used, and these bolts p p merely extend from the corner-irons F down through the sill. As above described, the corner-irons F are thus rigidly secured in place at the corners of the seat-buck by the 60 horizontal and vertical bolts n p, and at the same time the seat-risers E E are secured to and held rigid with the seat-buck by the lips l on the corner-irons.

65 With this construction of seat-buck braced and strengthened by the bolts and corner-irons a very rigid and durable construction is obtained. In addition to this the seat itself will rest securely and rigidly on the four corner-irons, and the weight of the occupants of the 70 vehicle will be distributed equally at the four corners instead of shifting from point to point, as it may do when the seat is mounted on the seat-risers.

75 Having thus described my invention, what I claim as new, and desire to secure by Letters Patent, is—

80 1. In a vehicle-body, the combination with the seat-buck of corner-irons, secured to the seat-buck at the four corners, said corner-irons 85 embracing the sides of the frame, with brace-rods extending through the corner-irons and the front and rear of the frame to brace the parts together.

85 2. In a vehicle-body, the combination with 90

the seat-buck, seat-risers of corner-irons secured to the seat-buck at the four corners, and to the seat-risers, said corner-irons embracing the sides of the frame, with brace-rods extending through the corner-irons and the front and rear of the frame to brace the parts together.

3. In a vehicle-body, the combination with the seat-buck, and seat-risers of corner-irons, secured to the seat-buck at the four corners, and to the seat-risers, said corner-irons embracing the sides of the frame, with brace-rods extending through the corner-irons and the front and rear of the frame horizontally

and through the side pieces and sill, vertically, 15 to brace the parts together.

4. In a vehicle-body, a corner-iron for bracing the corners of the seat-frame, consisting of a flat angular portion to embrace the side and end of the frame, having a flange to embrace the front of the cross-bar of the frame and a lip portion to be sunk into the top surface of the seat-riser. 20
